REMOVABLE GRILLE FOR VENTILATING APPARATUS

Gustav H. Koch, Springfield, Mass., assignor to Westinghouse Electric Corporation, East Pittsburgh, Pa., a corporation of Pennsylvania

Application June 2, 1949, Serial No. 96,653

12 Claims. (Cl. 98—40)

1

This invention relates to ventilating apparatus, and relates more particularly to removable grilles for use across air flow openings of such apparatus.

Grilles are commonly used across air inlet and outlet openings of ventilating apparatus, including air conditioning apparatus, for the purpose of improving the appearance, and in some cases for the further purpose of guiding and otherwise affecting the flow of air through such openings. It is necessary, or desirable, to remove such grilles from time to time, for cleaning the grilles or providing access to equipment mounted behind them.

This invention provides such a grille which can easily be snapped into place, and which can easily be detached without the use of tools.

In one embodiment of the invention applied to a home ventilating unit having a tubular wall around a propeller fan, and having an air inlet opening extending in a vertical plane at one end of the wall, one or a pair of spaced leaf springs are attached at their inner ends to the wall with their outer ends extending towards the inlet opening. The springs have apertures therein adjacent their outer ends. The grille has one or a pair of spaced lugs having projections, which may be provided by screw heads, that engage in the apertures in the springs when the grille is placed in its working position. An attempt to remove the grille by grasping its upper portion and exerting force on it to pull it away from the wall will be unsuccessful since it will be locked in position by the engagement of the projections or screw heads in the apertures in the springs. However, by grasping the lower portion of the grille and swinging it outwardly, the lugs on the grille will depress the outer ends of the springs so that the apertures and the projections will move apart and will become disengaged, following which the grille can be easily removed.

A feature of this invention is that the components for attaching the grille are completely concealed from view.

Another feature of this invention is that no tools are required for attaching and removing the grille.

An object of the invention is to provide a grille that can easily be inserted in and removed from an air opening, yet which will not accidentally disengage from the opening.

Another object of the invention is to provide a fastening means for a grille which will hold the grille securely against accidental removal, yet which can readily be released.

Another object of the invention is to provide

2

a fastening means for securing a grille in an air opening, which is concealed from view.

The invention will now be described with reference to the drawing, of which:

Fig. 1 is a perspective view of a home ventilating unit embodying this invention;

Fig. 2 is a vertical section taken along the line II—II of Fig. 1;

Fig. 3 is a transverse section taken along the line III—III of Fig. 2;

Fig. 4 is an enlarged, fragmentary view of a portion of the unit illustrated by Fig. 1;

Fig. 5 is a side elevation, partially in section, of the unit, and illustrates how the grille is released from the unit;

Fig. 6 is an enlarged section taken on the line VI—VI of Fig. 5; and

Fig. 7 is a section similar to Fig. 6, but showing the fastening means in locked position.

20 The home ventilating unit illustrated by the drawing, is of the so-called wall box fan type, and has a casing structure, including the tubular wall 10, which extends through a circular opening in the wall 12 to outdoors. Such a unit may be a kitchen ventilating unit or any other unit which draws air from an enclosure and exhausts it to outdoors.

25 The electric motor 13 is supported from the tubular wall 10 in any suitable manner (not shown). The propeller fan blades 14 are mounted on the shaft of the motor. Upon rotation of the fan blades by the motor, air is drawn into the unit through the inlet grille 17, and is exhausted through the conventional outlet structure 9 to outdoors.

30 The grille 17 may be formed from a suitable plastic, and which, in the embodiment of the invention illustrated by the drawing, extends vertically across the face of the unit at the inner 35 surface of the wall 12, consists of the outer ring member 24 and the inner ring members 25, 26 and 27 of increasingly smaller diameter, and which converge towards the horizontal axis of the unit. The ring members are interconnected by the 40 radially extending ribs 28, 29 and 30. The lowermost rib 30 has a recess 31 in its inner surface for receiving a chain guide 32 through which the chain 32a is extended.

45 The grille 17 has the lugs 33 and 34 formed on the back sides of the ribs 28 and 29 respectively, and which extend rearwardly therefrom perpendicular thereto. The lugs are so arranged that they just clear the inner surface of the tubular wall 10 when the grille is inserted in its operating 50 position. Each of the lugs 33 and 34 has an in-

wardly projecting portion 36 that reinforces the lug in transverse direction.

The lugs 33 and 34 have projections on their inner surfaces, spaced from the ends of the lugs and adapted to engage apertures in the grille supporting springs as will be described. These projections preferably comprise the heads 35 of screws that are threaded into the lugs.

For attaching the grille 17, the inner tubular wall 10 has spot welded to the upper portion of its inner surface at points equally spaced on opposite sides of the vertical axis of the unit, the inner ends of the cantilever leaf springs 18 and 19. As another feature of this invention, only the extreme inner ends of the springs are welded to the wall 10. The crosspieces 18a and 19a extend across and hold the springs 18 and 19 respectively, between the inner ends and the flexing portions thereof, and are spot welded at their ends to the wall 10. Thus the flexing portions of the springs are not subjected to the embrittling heat of the welding.

The unsupported outer ends of the springs 18 and 19 are biased towards the adjacent inner surface of the wall 10, and are curved in the arcs 20 towards the horizontal axis of the unit. The ribs 28 and 29 of the grille are in alignment with the springs 18 and 19 respectively, and conceal them from view when the grille is in its operating position in the unit.

In installing the grille 17 in the unit, the recess 31 is placed over the guide box 32, and the lugs 33 and 34 are lined up with the springs 18 and 19 respectively. The grille is then moved inwardly until the lugs 33 and 34 extend between the springs 18 and 19 respectively and the adjacent inner surfaces of the tubular wall 10, and the inner ends of the lugs contact the upper surfaces of the springs. The grille is then swung inwardly so that the inner ends of the lugs depress the outer ends of the springs, and slide along the upper surfaces of the springs until the screw heads 35 snap into the apertures 22 and 23 in the springs. The lugs will now rest upon the springs and support the grille therefrom as best illustrated by Fig. 3 of the drawing.

An attempt to remove the grille by grasping, and attempting to pull outwardly, its upper portion, will be unsuccessful since it will be securely locked in position by the engagement of the screw heads 35 in the apertures 22 and 23 in the springs 18 and 19 respectively. The side of the screw head 35 which is to the right in Figs. 6 and 7 constitutes an outwardly facing shoulder, and the right hand edge of the aperture 22 constitutes an inwardly facing edge. Such inwardly facing edge and outwardly facing shoulder provide the locking action.

However, the grille can easily be removed by grasping its lower portion and swinging it upwardly about its upper portion. When this is done the lugs 33 and 34 are so tilted that their inner ends depress the springs 18 and 19 respectively, so that the apertures in the springs, and the screw heads 35, are moved apart until they disengage, as shown in Fig. 6, following which the grille is easily removed.

The disengaging effort is minimized because of the leverage provided by the vertical dimension of the grille relative to the lugs 33 and 34.

It will be noted that as the lugs 33 and 34 are tilted, counterclockwise as shown in Fig. 6, the leaf springs 18 and 19 will tilt in the opposite direction, clockwise as shown in Fig. 6, thereby drawing the lugs and the spring apart toward

the outer ends of the springs. These screws having the heads 35 are disposed a sufficient distance from the inner or unsecured ends of the lugs 33 and 34 so that the screw heads 35 are disengaged from the apertures 22 and 23 in the springs upon such tilting.

It is to be noted that Fig. 6 is a section taken on a plane located sixty angular degrees from the top so that the outer ring member 24 is spaced from the flange of the tubular wall 10, whereas Fig. 5 shows the uppermost portion of the member 24 bearing against such flange.

While I have shown and described an embodiment having two leaf springs and two detents, it is to be understood that the invention is not so limited but that any suitable number of leaf springs and like number of detents may be used. It is also to be understood that the invention may be used in connection with a rectangular opening in which case one or a plurality of springs, with corresponding detent means, may be provided along the top of the opening and the grille.

While I have shown my invention in but one form, it will be obvious to those skilled in the art that it is not so limited, but is susceptible of various changes and modifications without departing from the spirit thereof.

30 What I claim is:

1. Ventilating apparatus comprising a grille support having an air flow opening, a grille extending across said opening, and means for supporting and latching said grille comprising a member on one portion of said grille extending inwardly of said support into said opening, a detent on the inner surface of said member, a cantilever spring attached to said support with its free end extending towards said opening, said member extending between said free end of said spring and the adjacent surface of said support, said free end of said spring being biased towards said member, and means carried by said free end of said spring for engaging said detent, said member being adapted when the opposite portion of the grille is swung away from the support, to move the free end of the spring away from the detent for disengaging same so as to permit withdrawal of the member from the opening.

2. Ventilating apparatus as claimed in claim 1 in which the fixed end of the spring is welded to the support, and a crosspiece extends across the spring between its fixed and free ends, and is welded at its ends to the support.

3. Ventilating apparatus comprising a tubular wall forming an air flow passage, a circular grille extending across said wall at one end thereof, and means for supporting said grille from, and for latching said grille to, said wall, comprising a pair of spaced members extending from said grille at one side of the center thereof into said passage, detents on the inner surfaces of said members spaced from the ends thereof, cantilever springs attached to the inner surface of said wall with their free ends extending towards said grille in alignment with said members and between same and the longitudinal axis of the wall, said free ends of said springs being biased towards said members, and detent engaging means carried by said springs adjacent their free ends, said members being adapted when the opposite side of the grille is swung away from the wall, to move the free ends of the springs away from the detents for disengaging same so as to

permit withdrawal of the members from the wall.

4. Ventilating apparatus as claimed in claim 3 in which the fixed ends of the springs are welded to the wall, and crosspieces extend across the springs between their fixed and free ends, and are welded at their ends to the wall.

5. Ventilating apparatus comprising a horizontal, tubular wall forming an air flow passage and having one end forming an opening extending in a vertical plane, a grille extending across said opening, and means for supporting said grille from, and for latching said grille to, said wall, comprising a member on the upper portion of said grille extending inwardly of said wall into said opening, a detent on the lower surface of said member spaced from the inner end thereof, a cantilever spring attached to said support and having its free end extending below said member towards said opening, said free end of said spring being biased towards said member, and detent engaging means carried by said free ends of said spring, said member being adapted when the lower portion of the grille is swung away from the wall to move the free end of the spring away from the detent for disengaging same for permitting the removal of the member from the wall.

6. Ventilating apparatus as claimed in claim 5 wherein a member, a detent, a cantilever spring and a detent engaging means are disposed on each side of and spaced from the vertical center line of said tubular wall.

7. Ventilating apparatus as claimed in claim 6 in which the free ends of the springs are curved inwardly towards the longitudinal axis of the tubular wall.

8. Ventilating apparatus as claimed in claim 6 in which the fixed ends of the springs are welded to the tubular wall with crosspieces extending across the springs between their fixed and free ends, and are welded at their ends to the wall.

9. Ventilating apparatus as claimed in claim 6 in which the detent engaging means are apertures in the springs.

10. Ventilating apparatus as claimed in claim 6, in which the free ends of the springs are curved inwardly towards the longitudinal axis of the tubular wall, and in which the detent engaging means are apertures in the springs adjacent their curved ends.

11. Ventilating apparatus as claimed in claim 6 in which the members extend from the rear surfaces of radially extending ribs on the grille, the ribs having sufficient width to conceal the members and their associated springs from view from the front of the grille.

12. Apparatus comprising a grille support having an opening therein, a grille extending across said opening, and means for latching said grille to said support comprising a member on said grille extending transversely therefrom into said opening adjacent the periphery of the opening, an outwardly facing shoulder on the inner side of said member and spaced from the free end thereof, and a relatively flat spring attached to said support, said spring bearing against the inner face of said member adjacent the free end thereof and having an inwardly facing edge adapted to engage the shoulder on said member, the free end portion of said member being adapted, when the opposed portion of the grille is swung away from the support, to move the spring away from said shoulder for disengaging said inwardly facing edge therefrom, thereby permitting withdrawal of the member from the opening.
